UNITED STATES PATENT OFFICE.

LEONARD KROWER, OF NEW ORLEANS, LOUISIANA.

DESIGN FOR A CLOCK-CASE.

SPECIFICATION forming part of Design No. 18,605, dated September 11, 1888.

Application filed July 9, 1888. Serial No. 279,484. Term of patent 3½ years.

To all whom it may concern:

Be it known that I, LEONARD KROWER, a subject of the King of the Netherlands, residing at New Orleans, in the parish of Orleans and State of Louisiana, have invented and produced a new and original Design for a Clock-Case; and I do declare the following to be a full, clear, and exact description of the invention, such as will enable others skilled in the art to which it appertains to make and use the same.

The figure of the drawing is a perspective view of my newly-designed clock-case.

The leading feature of my design consists in a cotton-bale-shaped clock-case, the outlines of which, when viewed as shown in the figure, show a case formed in shape of a cotton bale with bands or ties in position and a dial of clock on side of bale, the same being supported by claw-shaped feet and legs.

A is the top of case, which is circular in 20 its general contour. B is the side of case. C are bands or ties which encircle the case. D is an end view of case, which presents a flat surface. E are claw-shaped feet and legs which support front portion of case. F are legs which 25 support rear portion of case. G is dial of clock, the whole form presenting to the eye the combined effect of a cotton-bale-shaped clock-case resting in front on claw-shaped feet and legs.

I claim—

A design for a clock-case having the shape and configuration herein shown and described.

In testimony whereof I affix my signature in presence of two witnesses.

LEONARD KROWER.
